TRANSMISSION LINE JOINT

Cyrus H. Fraser, Washington, D. C.

Application June 12, 1941, Serial No. 397,771

18 Claims. (Cl. 174—21)

(Granted under the act of March 3, 1883, as
amended April 30, 1928; 370 O. G. 757)

This invention relates to a joint to be used in a radio transmission line between two sections of the line, one of which must be rotated with respect to the other.

Radio transmission lines are used to conduct power from a radio transmitter or from an antenna to a receiver. The transmission line is composed of an outer tubular conductor and an inner conductor with air or another dielectric between them. Usually the inner conductor is from about $\frac{1}{8}$ " to 1" in diameter and the outer conductor from $\frac{1}{4}$ " to 3" in outside diameter. The inner conductor is suspended within the outer conductor and centered by insulators usually of the ceramic type, which are fastened at regular intervals along the inner conductor.

Such transmission lines are usually filled with a gas under a pressure of from 10 to 20 pounds above atmosphere in order to prevent moisture from reaching the insulators on the inner conductor and destroying their insulating value. For several years there has been a need for a transmission line connection to an antenna which would allow the antenna to be rotated without appreciable loss of gas from the line over a period of several months. Such a connection to a rotating antenna must be so constructed that it will not introduce an impedance irregularity in the flow of radio frequency power to and from the antenna. In order to prevent the occurrence of such an irregularity the joining means between the stationary and rotating parts of the transmission line must avoid the use of fittings which would have the effect of causing a discontinuity in the size and spacing of the inner and outer conductors of the transmission line.

An impedance irregularity as discussed above results in a loss of power and becomes increasingly important as the frequency of the radio transmission increases.

It is an object of this invention to provide a joint which will allow relative rotation between sections of a transmission line with allowing any appreciable escape of gas from the line over a period of several months. It is a further object of the invention to provide such a joint which will not create a change in the impedance characteristics in the line. It is a still further object of the invention to provide such a joint utilizing a confined body of lubricating fluid as a portion of its sealing mechanism while at the same time preventing any leakage of said lubricating fluid into the interior of the line. Other objects of the invention will become apparent from a consideration of the following description taken to-

gether with the accompanying drawings, in which:

Fig. 1 is a view partly in section taken along the axis of a transmission line and showing a joint embodying the invention;

Fig. 2 is a view similar to Fig. 1 showing the arrangement for maintaining a supply of oil in the joint;

Fig. 3 is a view similar to Fig. 1 showing a second embodiment of the invention employing a single seal;

Fig. 4 is a view similar to Fig. 1 showing a third embodiment of the invention making use of concentric oil chambers;

Fig. 5 is similar to Fig. 1 showing an embodiment of the invention adapted for use with horizontally extending transmission lines;

Fig. 6 is a view similar to Fig. 1 showing another embodiment of the invention in which the seals of Fig. 1 have been replaced by packing;

Fig. 7 is a view similar to Fig. 1 showing another embodiment of the invention illustrating the use of a seal of a different type than that shown in Fig. 1; and

Fig. 8 is a side view of an enlarged portion of the outer conductor.

In the embodiment shown in Figs. 1 and 2 reference numeral 1 indicates the outer conductor of a transmission line having a concentric inner conductor 2 spaced from the outer conductor by means of a plurality of ceramic insulators 3. The space between the conductors is intended to be supplied with a gas at a pressure, for example, from 10 to 20 pounds above atmospheric. The outer conductor is shown as split into two sections at 4, the upper end of the lower section being of slotted construction resulting in a provision of a plurality of fingers 5 into which the lower end of the upper section is inserted. The inner conductor is provided with a similar joint at 6 having a plurality of fingers 7. The complete joint of the inner conductor is shown on Fig. 2. The material of the conductors is of a springy nature which enables the fingers 5 and 7 to snugly grip the opposed section while still allowing rotation between sections.

The sealing means for this joint is contained in a housing 8 which surrounds the transmission line and is provided with a sleeve 9 snugly fitting the outer conductor of the transmission line and extending above the joint 4. The upper end of this sleeve is connected in a gas-tight manner to the lower end of the upper section of the outer conductor as shown at 10. This connection may be soldered or welded. Snugly fitting around the

lower section of the outer conductor is a sleeve 11 of some material, such as stainless steel, which will take a high polish and provide rigidity. The lower end of this sleeve is also connected in a gas-tight manner to the outer conductor by soldering or similar means of connection as shown in 12. This sleeve extends upwardly inside the housing 8 and is provided with a pair of stepped bearing surfaces 13 and 14 upon which rotate oilless bearings 15 and 16 which form a part of the housing 8. As an additional safeguard against inadequate bearing lubrication, oil chambers 17 and 18 are provided in the housing 8 behind these bearings in order to provide the bearing metal with a constant supply of oil. Ducts are provided for filling these reservoirs, which ducts are normally closed in a gas-tight manner by means of threaded plugs 19 and 20.

The housing 8 is divided into 3 sections, 21, 22 and 23, sections 21 and 23 containing the oil reservoirs 17 and 18 respectively, and the section 22 being a hollow cylindrical member which is secured to sections 21 and 23 by lag bolts 24 and 25. The walls of section 22 are spaced from the sleeve 11 to provide an oil chamber 26. At each end of this chamber is secured in a gas-tight manner by flanges formed on abutting sections of the housing, a soft steel ring 27 or 28 in which is imbedded a bronze ring 29 or 30. Against one face of each of these rings is held a ring of hard steel 31 or 32. These steel rings are held against the respective bronze rings by means of a spiral spring 33 which surrounds the transmission line and has its ends abutting against a pair of housings 34 and 35 in which are contained synthetic rubber gasket rings 36 and 37. The rings 36 and 37 are L-shaped in cross-section, having one portion snugly fitting the sleeve 11 and the other portion abutting the hard steel rings 31 or 32. The abutting faces of sealing rings 29, 31 and 30, 32 are lapped to optical flats. The chamber 26 is kept completely filled with oil. The frictional contact of rings 36 and 37 with sleeve 11 is such that housings 34 and 35 and the rings which they enclose will partake of the movements of sleeve 11 and there will be no loss of gas between the rings 36 and 37 and the surface of sleeve 11.

This type of joint is adapted for use in a vertical position. When so used the level of the oil in chamber 26 will always be below the level of the break in the transmission line which will prevent oil from entering the transmission line. In order to avoid any conduction of oil between the upper portion of the lower section of the line and the surrounding sleeve 9, the outer diameter of the outer conductor is reduced over an area including the lower portions of the fingers 5 as shown at 75 in Fig. 8.

In Fig. 2 is shown the means for filling the reservoir 26. It consists of a boss 38 formed on part 23 of the housing and having a chamber 39 therein. A filling duct 40 is normally sealed by means of a threaded plug 41. Extending from near the top of this chamber down into the reservoir 26 is a pipe 42 which acts as an air vent to permit the escape of air from reservoir 26 when it is being filled with oil. A duct 43 extends from the bottom of the chamber 39 into the reservoir 26 for the passage of oil therethrough. Only the lower part of duct 43 is shown in dotted lines in Fig. 2, the upper portion being located behind pipe 42. A plastic window 44 is shown provided for the purpose of rendering visible the level of the oil in chamber 39.

In this embodiment of the invention the hous-

ing 8 is constructed to rotate with the upper section of the transmission line which leads to the antenna. It is shown in Fig. 1 as being supported by a member 45 which is also part of the rotating structure. The friction of the synthetic rubber rings 36, 37 is such that these rings, the spring 33 and the hard steel rings 31, 32 will all rotate with sleeve 11 so that relative movement occurs between rings 30 and 32 and between rings 29 and 31.

Any leakage of gas between the two conductors of the transmission line must proceed from the fingers 5 downwardly between the sleeve 11 and the bearing ring 16, thence along the sleeve 11 and out into chamber 26 by way of the abutting surfaces of rings 30 and 32. Any leakage of gas which takes place into reservoir 26 serves to increase the pressure on the oil in that reservoir until the pressure on the oil is equal to the pressure in the transmission line, at which time no further leakage into reservoir 26 will occur.

Leakage of gas from chamber 26 can be completely stopped at all its gasket joints. Any leakage of gas out of the chamber must then occur by passage of gas between the abutting faces of rings 29 and 31 to the surface of sleeve 11 and thence out between the surface of sleeve 11 and the bearing sleeve 15. Experience has shown, however, that over a period of several months no leakage of gas whatsoever will occur.

Another embodiment of the invention is shown in Fig. 3 wherein the housing 8 remains stationary while the upper section of the transmission line rotates with respect thereto. In this embodiment a sleeve 46 terminates above the lower end of the upper section of the outer conductor and is connected thereto by a gas-tight means such as solder shown at 47. The sleeve extends downwardly past the joint, finally terminating at 74 within the lower part of housing 8. The upper part of sleeve 46 is supported in a packed joint formed at the upper end of housing 8. Immediately beneath this joint it is rotatively supported by means of a ball bearing assembly 50. Beneath this assembly a flange 48 is formed on the sleeve and the sleeve is then continued downwardly with a uniform diameter until near its lower end where its diameter is reduced to form a shoulder indicated at 51. Beneath the shoulder 51 the lower end of the sleeve is supported by means of an oilless bearing 52. While bearing 50 has been shown as a roller bearing and 52 as an oilless bearing, it should be understood that the type of bearing used is not material to the invention. Just above the shoulder portion 51 of the sleeve 46 is secured a ring 53 preferably of bronze, this ring being held in place against rotation by flange 54 formed on a portion of the housing 8. A gasket 76 extending across the entire width of the side wall of housing 8 and the flange 54, together with a gasket 98 beneath the ring 53, aid in holding the ring against rotation and prevent gas leakage beneath the ring and out through housing 8 at this point. Bearing against the bronze ring 53 is a sealing assembly of the same type as shown in Figs. 1 and 2 composed of a hard steel ring packed with a synthetic rubber ring and a spring. It should be understood that where sealing assemblies of this type are mentioned that the materials, bronze and steel, are mentioned only by way of illustration. Such seals are conventional and the materials usually employed are bronze and steel, the purpose being to provide one hard and one soft bearing surface. It is not material which of the rings is bronze and which is

steel, nor that these particular metals be used. The upper end of the spring 33 abuts against the flange 48. The reservoir 26 is filled with oil as in Figs. 1 and 2. The lower end of the housing 8 is secured by a gas-tight means such as soldering to the lower stationary portion of the conductor as shown at 55.

In operation the housing 8, the lower section of the transmission line and ring 53 remain stationary. The upper section of the transmission line together with sleeve 46 and the sealing assemblies consisting of spring 33 and the rubber and steel rings rotate together. Any gas leaking from the joint in the transmission line must pass downwardly beneath sleeve 46, out at its lower end 74, back over its outer surface under bearing ring 52, thence under ring 53 and out into chamber 26 through the seal. To leak from the chamber 26 the gas must pass upwardly through the packed joint at the upper end of housing 8. Oil 20 obviously cannot leak into the interior of the transmission line either in this embodiment or in that shown in Figs. 1 and 2, since the oil level is at all times below the joint.

The embodiment shown in Fig. 4 is somewhat similar to that of Fig. 3 but employs a pair of concentric oil reservoirs and a pair of concentric seals. A sleeve 56 is secured to the lower end of the upper section of the outer conductor by means of a gas-tight seal shown at 57. It extends downwardly over the transmission line joint and terminates just inside the lower end of the housing 8 as in Fig. 3 at point 58. The upper portion of the sleeve is supported in a packed joint formed in the upper part of housing 8 and beneath this joint is supported by ball bearing assembly 59. Beneath the ball bearing assembly 59 the diameter of the sleeve increases at a shoulder 60 and below this point it flares out into a wide flange 61 having dependent therefrom a skirted portion 62, the flange extending beyond the skirt. The housing is divided into three parts, the lowermost of which is numbered 63. Overlying part 63 and extending between sleeve 56 and the walls of housing 8 is a steel ring 65 which is held down against rotation with respect to housing 8 by means of a flange 67 formed on the inner walls of housing 8. A gasket 64 forms a gas-tight seal between the lower surfaces of the side walls of housing 8 and the ring 65 and the upper surface of part 63. A pair of spaced, annular, upwardly extending flanges 66 and 71 are formed on ring 65 and against the flat upper surface of each of these flanges is pressed a seal assembly such as shown in Figs. 1 and 2 described above, consisting of a spring pressing against a housing containing a rubber ring and a steel ring, the upper ends of the springs of these assemblies being pressed against the flange 61. The rubber ring of the assembly which cooperates with flange 71 fits snugly against the outer surface of skirt 62 while the corresponding rubber ring cooperating with flange 66 is pressed against the outer surface of sleeve 56. The skirt 62 together with the seal carried thereon and flange 71 divide the interior of housing 8 into 2 chambers, the inner one marked 68 and the outer 69. Chamber 68 is filled with oil through a filling hole shown sealed by plug 70 while chamber 69 is filled through filling hole shown sealed by plug 71. Air vents 78 and 79 are provided. The lower end of housing 8 is secured in a gas-tight manner to the lower section of the transmission line at 72. The lower end of the sleeve 56 is supported by means of an oilless bearing 73.

Any gas leaking out of the transmission line must travel downwardly of the sleeve 56 through its lower end 58 and from thence up between sleeve 56 and bearing 73, then out into chamber 68 by way of the seal cooperating with flange 66, from thence into chamber 69 by way of the seal cooperating with flange 71 and out through the packed joint surrounding the upper end of sleeve 56. As in the preceding embodiments, oil cannot leak into the interior of the transmission line, since its level never rises above the joint. In this embodiment the housing 8 is stationary while the sleeve 56 and the sealing means carried thereby revolve with the upper section of the transmission line.

Fig. 5 shows an embodiment of the invention adapted for use with a horizontally extending transmission line. It employs a housing 8 of the same general type as used in the preceding embodiments which is secured in a gas-tight manner at 80 to the left hand or rotating end of the transmission line. A sleeve 81 is shown fitted over the right hand or stationary end of the transmission line and secured thereto in a gas-tight manner at both its ends as indicated at 82 and 83. The central portion of the sleeve is of larger diameter than the end portions, which latter portions are supported for rotation in oilless bearings 84 and 85. The right hand end wall of housing 8 carries imbedded therein a bronze ring 86. The central portion of housing 8 comprises a thick cylinder 87, the inner diameter of which is enlarged by a shoulder 88 near its left hand end. Bolted to the shoulder 88 is an annular disc 89 having imbedded near its central edge a bronze ring 90. Abutting against the bronze rings 86 and 90 are a pair of seals of the type shown in Figs. 1 and 2 which are forced against rings 86 and 90 by means of a spiral spring in a manner described in Fig. 1. This arrangement provides a large diametered chamber 91 to the left of disc 89. Secured to the sleeve 81 within this chamber are a pair of oil throwing discs 91 and 92. The reservoir to the right of disc 89, marked 93, is kept completely filled with oil in the previously described manner through oil hole 94 which is normally sealed in a gas-tight manner by means of plug 95.

In this embodiment the housing 8 rotates with the left hand section of the transmission line while the right hand section of the transmission line together with sleeve 81 and the seals carried thereby remain stationary. However, the right hand section may be rotated while the left hand section remains stationary, if desired. Any gas leaking from the transmission line must pass to the right between the outside of sleeve 81 and the bearing 85, thence by way of the seal cooperating with ring 90 into the chamber 93 and from there by way of the seal cooperating with ring 86 it must pass out of chamber 93 and thence between sleeve 81 and bearing 84 to the outside of the housing. Any oil which may succeed in passing the seal associated with ring 90 will be trapped by oil thrower discs 91 and 92 and be thrown to the walls of chamber 87, in the bottom of which it will accumulate. A drain hole closed gas-tight by plug 96 is provided for draining this chamber.

The embodiment illustrated in Fig. 6 is similar to that in Figs. 1 and 2 with the exception that in this embodiment packed joints have been substituted for the seals shown in Figs. 1 and 2. The housing 8 has an upwardly extending portion 100 which fits snugly over the joint in the transmission line and the upper end of which is sealed in a

gas-tight manner to the upper or rotating section of the transmission line at 101. A sleeve 102 is fitted over the lower or stationary section of the transmission line near the joint, and this is provided with two stepped bearing portions 103 and 104 which are supported for rotation by bearings 105 and 106. The portion 100 of housing 8 carries a dependent skirt 107 having an internal diameter greater than that of the external diameter of portion 102 of the sleeve. Within the annular space formed between the skirt and sleeve are fitted packing means 108 which are compressed by means of a thimble 109 threaded into the lower end of the skirt. A similar skirt extends downwardly from the lower portion of housing 8 and packing 110 is compressed within this skirt by means of thimble 111. The interior of housing 8 surrounding the upper skirt 107 comprises a chamber 112 which is kept filled with oil by means of an oil filling duct 113 normally closed in a gas-tight manner by means of plug 114. The lower end of sleeve 104 is secured in a gas-tight manner by means of plug 114. The lower end of sleeve 104 is secured in a gas-tight manner to the lower portion of the transmission line as indicated at 115.

Any gas leaking from the transmission line must pass downwardly over the exterior of the sleeve between the portion 103 and bearing 105 and thence between the portion 102 and the packing 108 into chamber 112 from where it must pass between portion 104 and bearing 106 and then downwardly between portion 104 and packing 110 to the outside of housing 8.

Many other sealing arrangements involving packing and embodying the invention may be resorted to. For example, resilient means may be interposed between the packing material 108 and 110 and their respective thimbles 109 and 111. Another possible construction is the reversal of the lower skirt and the replacement of thimbles 109 and 111 by a common resilient means acting on both sets of packings.

In Fig. 7 is shown an embodiment of the invention employing a type of seal which varies somewhat from those previously discussed. A sleeve 120 is secured in a gas-tight manner to one section of the transmission line as shown at 121. The ends of the sleeve are supported by bearings 122 and 123. The housing 8 is divided into three portions, the uppermost portion of which carries a ring 129 of synthetic rubber or similar material in which is imbedded a bronze ring 124. The central portion of the sleeve has secured immovably thereto as by soldering or welding, a ring 125 of hard steel. The ring may, if desired, be an integral part of the sleeve, formed by machining processes. The lowermost section of housing 8 has imbedded therein a bronze ring 126 against which is forced the hard steel ring of a spring pressed seal assembly such as was described in connection with Figs. 1 and 2. The upper end of the spring of this assembly abuts against ring 125. The lower end of housing 8 is secured in a gas-tight manner to the lower section of the transmission line as shown at 127. The upper end of the spring of the seal assembly bears against ring 125 and tends to force upwardly this ring together with sleeve 120 and the left hand section of the transmission line, thus maintaining a seal between ring 125 and 124. At the same time the spring also maintains a seal with respect to ring 126. Any gas escaping from the transmission line must pass upwardly between the sleeve and the bearing 123 and thence out into the oil

filled central chamber 128 of housing 8 by way of the seal cooperating with ring 126 and from there by way of the seal between ring 124 and 125 between the bearing 122 and the sleeve to the outside of housing 8. The position of the break in the transmission line above the oil level of chamber 128 prevents leakage of oil into the line.

While a reinforcing sleeve has been shown in each of the illustrated embodiments of the invention, such a sleeve is necessary only in certain types of joints. In those types illustrated by Figs. 1, 5, 6 and 7, the sleeve may be dispensed with if the outer conductor is made strong enough and of proper material and configuration to do the work assigned to the sleeve in the joints illustrated by these figures. These changes in the dimensions and thickness of the outer conductor will not cause an impedance irregularity if the inner diameter and configuration of the conductor is not altered.

While these joints have been described with particular reference to radio transmission lines, it is obvious that they are applicable wherever it is desired to prevent the escape of fluid around a rotating shaft or pipe passing through a bearing.

The invention may be used, for example, to prevent the passage of a liquid between a shaft and a bearing in which it turns. An instance of such a use would be to prevent the entry of sea water around the propeller shaft of a boat. Applicant has disclosed several embodiments of the invention and doubtless many changes in proportions, materials and arrangement are possible without exceeding the scope of the invention. For example, packing may be substituted for the other types of seals shown. It is to be understood in this connection that the invention is to be considered as limited only by the scope and limitations of the appended claims.

The invention described herein may be manufactured and/or used by or for the Government of the United States of America for governmental purposes without the payment of any royalties thereon or therefor.

I claim:

1. Means for preventing the escape of gas under pressure from the interior of a radio transmission line having two sections mounted for rotation relative to each other, without interfering with said rotation, said means comprising a housing surrounding the adjacent ends of said section, means forming an integral gas-impervious connection between said housing and one of said sections around the entire periphery of said section, a reinforcing sleeve of bearing material fitted snugly around and integrally connected to the other of said sections in a gas-impervious manner around the entire periphery of said section, a pair of bearing means carried by said housing, each of said bearing means surrounding a portion of said sleeve, said housing being so shaped as to form a gas-tight chamber around said sleeve intermediate said bearings, ring means carried at each end of said chamber in gas-tight relation to the walls thereof, each of said ring means fitting snugly around said sleeve and having a flat bearing surface, a pair of ring-like sealing means fitted around said sleeve between said ring means, each of said sealing means having a flat surface mating with one of said first-mentioned flat surfaces, resilient means carried by said sealing means and snugly fitting around said sleeve whereby to prevent passage of gas between said sealing means and said sleeve and to cause said sealing means to rotate with

said sleeve, means urging each of said sealing means against one of said ring means until the said flat surface carried by said sealing means is forcefully pressed against the said mating surface of said ring means and a body of lubricating fluid substantially completely filling said chamber.

2. A means for preventing the escape of gas under pressure from the interior of a radio transmission line having two sections joined for rotation relative to each other, without interfering with said rotation, said means comprising a housing so shaped as to form a closed chamber enclosing a portion of one of said sections and having end walls forming bearings for the rotation of said section therein, a portion of said housing extending from one of said bearings across said joint and being integrally secured to the other of said sections in a gas-impervious manner around the entire periphery thereof, and means sealing said chamber against leakage of gas therefrom by way of the one of said bearings nearest said joint, said means including a gas-impervious extension of the end wall of said housing nearest said joint, and means encircling said one of said sections in a gas-impervious manner and in non-rotating relation thereto, said extension and said last named means having mating surfaces, means pressing said mating surfaces together over an area completely encircling said one of said sections, and a body of lubricating fluid substantially completely filling said chamber.

3. Means for preventing the escape of gas under pressure from the interior of a radio transmission line having two sections mounted for rotation relative to each other, without interfering with said rotation, said means comprising a housing surrounding the adjacent ends of said sections, means forming an integral gas-impervious connection between said housing and one of said sections around the entire periphery of said section, said housing being so shaped as to form a gas-tight chamber enclosing a portion of the other of said sections and having bearing means in its opposite walls in which said section rotates, a ring means carried at each end of said chamber forming an annular gas-tight extension of said chamber walls, each of said ring means fitting snugly around said section and having a flat bearing surface, a pair of ring-like sealing means fitted around said section between said ring means, each of said sealing means having a flat surface mating with one of said first-mentioned flat surfaces, resilient means carried by said sealing means and snugly fitting about said other of said sections whereby to prevent passage of gas between it and said section and to cause said sealing means to rotate with said section, means urging each of said sealing means against one of said ring means until the said flat surface carried by said sealing means is forcefully pressed against the said mating surface of said ring means, and a body of lubricating fluid completely filling said chamber.

4. A means for preventing the escape of gas under pressure from the interior of a radio transmission line having two sections joined for rotation relative to each other, without interfering with said rotation, said means comprising a housing so shaped as to form a closed chamber enclosing a portion of one of said sections and having end walls forming bearings for the rotation of said section therein, a portion of said

housing extending from one of said bearings across said joint and being integrally secured to the other of said sections in a gas-impervious manner around the entire periphery thereof, and means sealing said chamber against leakage of gas therefrom by way of the one of said bearings farthest from said joint, said means including a gas-impervious extension of the end wall of said housing farthest from said joint, and means encircling said one of said sections in a gas-impervious manner and in non-rotating relation thereto, said last two means having cooperating annular bearing surfaces encircling said one of said sections, means pressing said bearing surfaces tightly together, and a body of lubricating fluid substantially completely filling said chamber.

5. A means for preventing the escape of gas under pressure from the interior of a radio transmission line having two sections joined for rotation relative to each other, without interfering with said rotation, said means comprising a stiffening sleeve of bearing material fitting over the adjacent ends of said sections, means forming an integral gas-impervious connection between said sleeve and one of said sections, a housing shaped to form a chamber surrounding a portion of said sleeve, and having end walls in which said sleeve is journaled for rotation relative to said housing, the end wall of said housing farthest from said connection being extended into engagement with the periphery of the other of said sections, means forming an integral gas-impervious connection between said end wall and said section completely encircling said section and sealing means formed between said end wall and said sleeve, said sealing means comprising a ring-shaped member in gas-impervious relation to said end wall, said ring-shaped member having a bearing surface, a sealing member encircling said sleeve in a gas-impervious manner and in non-rotative relation thereto, said sealing member having a bearing surface mating with said first-mentioned bearing surface, an abutment formed on said sleeve and spaced from said sealing member, resilient means surrounding said sleeve between said abutment and said sealing member and tending to press said bearing surfaces tightly together over an area completely encircling said sleeve, a cylindrical skirt extending from said abutment in the direction of said end wall, a sealing means similar to said first-mentioned sealing means between said skirt and said end wall, said abutment extending beyond the periphery of said skirt, and resilient means surrounding said skirt between said abutment and said sealing means in the same manner as first-mentioned resilient means, and a body of lubricating fluid substantially completely filling said chamber both inside and outside of said skirt.

6. A means for preventing the escape of gas under pressure from the interior of a radio transmission line having two sections joined for rotation relative to each other, without interfering with said rotation, said means comprising a stiffening sleeve of bearing material fitting over the adjacent ends of said sections, means forming an integral gas-impervious connection between said sleeve and one of said sections, a housing shaped to form a chamber surrounding a portion of said sleeve, and having end walls in which said sleeve is journaled for rotation relative to said housing, the end wall of said housing farthest from said connection being extended into engagement

with the periphery of the other of said sections, means forming an integral gas-impervious connection between said end wall and said section around the entire periphery of said section and sealing means formed between said end wall and said sleeve, said sealing means comprising a ring-shaped member in gas-impervious relation to said end wall, said ring-shaped member having a bearing surface, a sealing member, encircling said sleeve in a gas-impervious manner and in non-rotative relation thereto, said sealing member having a bearing surface mating with said first-mentioned bearing surface, an abutment formed on said sleeve and spaced from said sealing member, resilient means surrounding said sleeve between said abutment and said sealing member and tending to press said bearing surfaces tightly together over an area completely encircling said sleeve, and a body of lubricating fluid substantially completely filling said chamber.

7. A means for preventing the escape of gas under pressure from the interior of a radio transmission line having two sections joined for rotation relative to each other, without interfering with said rotation, said means comprising a stiffening sleeve of bearing material fitting over the adjacent ends of said sections, means forming an integral gas-impervious connection between said sleeve and one of said sections, a housing shaped to form a chamber surrounding a portion of said sleeve, and having end walls in which said sleeve is journaled for rotation relative to said housing, the end wall of said housing farthest from said connection being extended into engagement with the periphery of the other of said sections, means forming an integral gas-impervious connection between said end wall and said section around the entire periphery of said section and sealing means formed between one of said end walls and said sleeve, said sealing means comprising a gas-impervious extension of said one of said end walls and a sealing member encircling said sleeve in a gas-tight manner and in non-rotative relation thereto, said sealing member and said sealing means having cooperating surfaces, means forcefully pressing said surface together over an area completely encircling said sleeve and a body of lubricating fluid substantially completely filling said chamber.

8. A means for preventing the escape of gas under pressure from the interior of a radio transmission line having two sections joined for rotation relative to each other, without interfering with said rotation, said means comprising a housing shaped to form a chamber surrounding a portion of one of said sections and having end walls in which said section is journaled for rotation relative thereto, the end wall of said housing nearest said joint being extended into engagement with the periphery of the other of said sections, means forming an integral gas-impervious connection between said end wall and said sections around the entire periphery of said section and sealing means formed between one of said end walls and said one of said sections, said sealing means comprising a ring of resilient material imbedded in said one of said end walls and surrounding said section, a ring of bearing material imbedded in said resilient ring and having a bearing face, a ring-shaped member of bearing material secured to said section in an integral non-rotative manner and having a bearing surface mating with said first-mentioned bearing surface, an abutment carried by said sleeve and spaced from said ring-shaped member, resilient means

surrounding said sleeve between said abutment and said ring-shaped member and tending to press said bearing surfaces tightly together and a body of lubricating fluid substantially completely filling said chamber.

9. A means for preventing the escape of gas under pressure from the interior of a radio transmission line having two sections joined for rotation relative to each other, without interfering with said rotation, said means comprising a housing shaped to form a chamber surrounding a portion of one of said sections and having end walls in which said section is journaled for rotation relative thereto, the end wall of said housing nearest said joint being extended into engagement with the periphery of the other of said sections, means forming an integral gas-impervious connection between said end wall and said section around the entire periphery of said section and sealing means formed between one of said end walls and said one of said sections, said sealing means comprising a ring of resilient material imbedded in said one of said end walls and surrounding said section, a ring of bearing material imbedded in said resilient ring and having a bearing face, a sealing member encircling said section in a gas-tight manner and in non-rotative relation thereto, and having a bearing surface mating with said bearing face, means forcefully pressing said bearing surface and said bearing face together and a body of lubricating fluid substantially completely filling said chamber.

10. Means for preventing the escape of fluid under pressure from the interior of a hollow cylindrical member composed of two sections joined together for relative rotation, comprising means joined to one of said sections in a fluid-tight manner around the periphery thereof and extending across said joint to form a wall having an opening in which the other of said sections is journaled, means forming a fluid-tight chamber around a portion of said member on the side of said wall from which said fluid would normally escape, said chamber forming means comprising a portion of said wall, means for preventing entry of said fluid into said chamber, said means comprising a packing means carried by said wall, means for preventing escape of any fluid which might leak into said chamber, said means comprising packing means carried by the portion of the wall of said chamber surrounding said member as it leaves said chamber, said portion of said chamber wall forming a bearing for said member and a body of lubricating fluid substantially completely filling said chamber, said body of lubricating fluid being only under such pressure as may build up in said chamber due to leakage of said fluid thereinto, said chamber being so dimensioned and located as to accommodate all of said lubricating fluid below the level of said joint.

11. Means for preventing the escape of fluid under pressure from the interior of a hollow cylindrical member composed of two sections joined together for relative rotation, comprising means joined to one of said sections in a fluid-tight manner around the periphery thereof and extending across said joint to form a wall having an opening in which the other of said sections is journaled, means forming a fluid-tight chamber around a portion of said member on the side of said wall from which said fluid would normally escape, said chamber forming means comprising a portion of said wall, a sealing means for pre-

venting entry of said fluid into said chamber, said sealing means comprising a pair of means having cooperating surfaces in sliding contact over an area completely encircling said member, means pressing said surfaces forcefully together, one of said pair of means being carried in fluid tight non-rotating relation to the periphery of said member and the other having the same relation to said wall, a similar sealing means for preventing escape of any fluid which might leak into said chamber, said last named sealing means being located inside said chamber and in fluid-tight relation to the portion of the wall of said chamber surrounding said member as it leaves said chamber, and a body of lubricating fluid substantially filling said chamber, said body of lubricating fluid being only under such pressure as may build up in said chamber due to leakage of said fluid thereinto, said chamber being so dimensioned and located as to accommodate all of said lubricating fluid below the level of said joint.

12. Means for preventing the escape of fluid under pressure from the interior of a hollow cylindrical member composed of two sections joined together for relative rotation, comprising means joined to one of said sections in a fluid-tight manner around the periphery thereof and extending across said joint to form a wall having an opening in which the other of said sections is journaled, means forming a fluid-tight chamber enclosing a section of said member on the side of said wall from which said fluid would normally escape, said chamber forming means comprising a portion of said wall, a sealing means for preventing entry of said fluid into said chamber, said sealing means comprising a pair of means, one of which is carried in fluid-tight non-rotating relation to the periphery of said member and the other having the same relation to said wall, each of said pair of means having a surface completely encircling said member and having a configuration conforming to that of the other of said surfaces, means pressing said surfaces together in an area of contact completely encircling said member, and a body of lubricating fluid substantially completely filling said chamber, said body of lubricating fluid being only under such pressure as may build up in said chamber due to leakage of said fluid thereinto, said chamber being so dimensioned and located as to accommodate all of said lubricating fluid below the level of said joint.

13. Means for preventing the escape of fluid under pressure from the interior of a hollow cylindrical member composed of two sections joined together for relative rotation, comprising means joined to one of said sections in a fluid-tight manner around the periphery thereof and extending across said joint to form a wall having an opening in which the other of said sections is journaled, means forming a fluid-tight chamber around a portion of said member on the side of said wall from which said fluid would normally escape, a sealing means for preventing the escape of any fluid which might leak into said chamber, said sealing means comprising a pair of means, one of which is carried in fluid-tight non-rotating relation to the periphery of said member and the other having the same relation to that portion of said chamber forming means which surrounds said member as it leaves said chamber, each of said pair of means having a surface completely encircling said member and having a configuration conforming to that of the other of

said surfaces, means pressing said surfaces together in an area of contact completely encircling said member, and a body of lubricating fluid substantially completely filling said chamber, said body of lubricating fluid being only under such pressure as may build up in said chamber due to leakage of said fluid thereinto, said chamber being so dimensioned and located as to accommodate all of said lubricating fluid below the level of said joint.

14. Means for preventing the escape of gas under pressure from the interior of a radio transmission line having two sections joined for rotation relative to each other, without interfering with said rotation, said means comprising a housing enclosing said joint and having two parts mounted for rotation relative to each other, each of said parts being a gas-tight extension of a different one of said sections and extending around the complete circumference thereof, each of said parts presenting a surface completely encircling said transmission line for cooperation with the corresponding surface on the other of said parts, and means acting on said parts to prevent the passage of gas between said surfaces, said means including a body of lubricating fluid substantially completely filling said housing, said body of lubricating fluid being only under such pressure as may build up in said housing due to leakage of said gas thereinto, said housing being so formed and dimensioned as to accommodate below the level of said joint all the lubricating fluid which may leak through between said surfaces toward said joint within a predetermined time.

15. Means for preventing the escape of gas under pressure from the interior of a radio transmission line having two sections joined for rotation relative to each other, without interfering with said rotation, said means comprising a housing enclosing said joint, said housing comprising a gas-impervious extension of one of said sections completely enclosing said joint and presenting a surface completely encircling the other of said sections for cooperation therewith, and means sealing the space between said surface and said other of said sections against the passage of gas therethrough, said means including a body of lubricating fluid substantially completely filling said housing, said body of lubricating fluid being only under such pressure as may build up in said housing due to leakage of said gas thereinto, said housing being so formed and dimensioned as to accommodate below the level of said joint all the lubricating fluid which may leak through between said surfaces toward said joint within a predetermined time.

16. Means for preventing the escape of fluid under pressure from the interior of a hollow vertical cylindrical member composed of two sections joined together for relative rotation, comprising a sleeve integrally secured in a fluid-tight manner about the periphery of the upper of said sections near said joint, said sleeve extending downwardly in snugly fitting relation over a portion of said lower section, a housing integrally secured in a fluid-tight manner about the periphery of the lower of said sections beneath said sleeve and enclosing a portion of said sleeve, a bearing for said sleeve formed in each of the upper and lower ends of said housing, means forming a pair of fluid retaining rotatable seals between said sleeve and said housing, said seals defining a chamber between said housing and said sleeve and a body

of lubricating fluid substantially filling said chamber.

17. Means for preventing the escape of fluid under pressure from the interior of a hollow cylindrical member composed of two sections joined together for relative rotation, comprising a sleeve integrally secured in a gas-tight manner about the periphery of one of said sections near said joint, said sleeve extending across said joint in snugly fitting relation over a portion of the other of said sections, a housing integrally secured in a fluid-tight manner about the periphery of said other section beyond said sleeve and enclosing a portion of said sleeve, a bearing for said sleeve formed in each end of said housing, means forming a pair of fluid-retaining rotatable seals between said sleeve and said housing, said seals defining a chamber between said housing and said sleeve and a body of lubricating fluid substantially filling said chamber.

18. Means for preventing the escape of gas under pressure from the interior of a hollow cylindrical member composed of two sections joined together for relative rotation, comprising a housing integrally secured in a fluid-tight manner about the periphery of one of said sections, extending across said joint and there being formed into a closed chamber having fluid impervious walls and surrounding a portion of the other of said sections, fluid-tight sealing means sealing the space between the periphery of said other section and the walls of said chamber where said section enters and leaves said chamber, a bearing means for said section carried by said housing and located between said sealing means, and a body of lubricating fluid substantially filling said chamber.

CYRUS H. FRASER.
